UNITED STATES PATENT OFFICE.

CHARLES ARTHUR SPEAKMAN, OF NEW YORK, N. Y., ASSIGNOR TO THE AMERICAN LITHOGRAPHIC COMPANY, OF SAME PLACE.

DESIGN FOR A LABEL.

SPECIFICATION forming part of Design No. 29,721, dated November 22, 1898.

Application filed August 5, 1898. Serial No. 688,325. Term of patent 7 years.

To all whom it may concern:

Be it known that I, CHARLES ARTHUR SPEAKMAN, a citizen of the United States, residing at New York city, in the county of

5 New York and State of New York, have invented and produced a new and original Design for a Label, of which the following is a specification, reference being had to the accompanying drawing, forming a part thereof.

10 My design is intended as a label.

In the accompanying drawing the design is shown upon a rectangular plane.

15 The design comprises a rectangular panel having thereon a shell-shaped panel framed by an irregular ribbon border A, with curves and loops which originate in an open wreath of leaves B.

C is a medal showing its obverse and reverse sides, behind which and extending right and left passes an ornamental ribbon 20 terminating in scrollwork ends.

D denotes an ornamental shield with a five-pointed star encircled by rays.

E and F denote medals similar to C, forming part of the outline of the design. 25

I claim—

The design for a label as herein shown and described.

In testimony whereof I affix my signature in the presence of two witnesses.

CHARLES ARTHUR SPEAKMAN.
